UNITED STATES PATENT OFFICE.

THOMAS G. KUS, OF CHICAGO, ILLINOIS, ASSIGNOR, BY MESNE ASSIGNMENTS, TO CHICAGO TRUST COMPANY, TRUSTEE, OF CHICAGO, ILLINOIS, A CORPORATION.

COKE-OVEN DOOR.

1,412,247.

Specification of Letters Patent. Patented Apr. 11, 1922.

Application filed February 16, 1920. Serial No. 359,097.

To all whom it may concern:

Be it known that I, THOMAS G. KUS, a citizen of the United States, residing at Chicago, Cook County, Illinois, have invented certain new and useful Improvements in Coke-Oven Doors and the like, of which the following is a specification.

This invention relates to certain improvements in the construction of doors and the like. The invention has particular reference to the construction of doors for use in connection with retort coke ovens, and for this reason, I have herein illustrated and will particularly describe the features of the present invention as applied to such use. I wish it distinctly understood, however, that in so doing I do not intend thereby to in any manner limit the application of the invention to such use except as I may do so in the claims.

Retort coke oven doors are relatively large and heavy, and are generally of considerably elongated form. It is common practice to line or face the inner surface of such doors with silica bricks or blocks, or other material of highly refractory nature. In order to prevent damage to such linings by jamming or striking against stationary portions of the ovens, it is very desirable to provide means on the doors whereby they can be very securely gripped and sustained by the door handling mechanism. One of the objects of the invention is to provide a construction of door and attachments therefor whereby the door handling apparatus may take such a definite and firm hold of the door as to effectually prevent any undesirable and improper movements of the door with respect to the door handling apparatus.

Another feature of the invention has to do with the construction of the locking devices whereby the door is held securely in position with respect to the oven. In this connection, one of the objects of the invention is to provide a very simple and effective locking device which may be readily attached to or detached from the door face without change of the construction of the door itself; and a locking device which in service will effectually co-operate with suitable stationary elements located for example, upon the buck-stays so as to lock the door in position.

Another feature of the invention has to do with the provision of a locking device

of such a construction that it may also be used as the means or element with which the door handling machine directly co-operates in the operation of removing the door from the oven or seating it in position. In this connection, another feature of the invention is to provide a locking device of such form and arrangement that in the normal operation of engaging it by the door handling machine it will be automatically unlocked from the stationary elements with which it co-operates in the locking function so that while serving the double purposes of a locking device and an element to be engaged by the lifting or handling mechanism, it is also so constructed that in the operation of engaging it by the lifting or handling mechanism the locking device is first unlocked from the stationary elements, so that when the time comes for removing or disengaging the door from the stationary structure, the door will be released or unlocked.

In this connection, a further object of the invention is to so associate or combine the door handling mechanism with the door and its locking devices that in the reverse operation of seating the door and disengaging the door handling element therefrom, the locking device will be automatically locked firmly in position so as to lock the door before the door handling machine is disconnected from it.

Other objects and uses of the invention will appear from a detailed description of the same which consists in the features of construction and combinations of parts hereinafter described and claimed.

In the drawings:

Figure 1 shows a face view of a coke oven door seated in position in the oven, and showing a typical construction of buck-stays adjacent thereto;

Fig. 2 shows a central vertical section corresponding to Fig. 1, the end or engaging portions of the lifting arms being shown in engagement with the door locking devices, so as to show the manner in which the parts co-operate;

Fig. 3 shows a fragmentary face view of the door with the locking device mounted thereon, said locking device being in locking engagement with the brackets on the buck-stays;

Fig. 4 shows a vertical section taken on the line 4-4 of Fig. 3 looking in the di-

rection of the arrows, the lifting jaw being raised so as to raise the locking bar to the upper ends of the slots; and

Fig. 5 shows a plan section corresponding to Figs. 3 and 4.

In the drawings, I have illustrated the features of the invention as being applied to a coke oven construction in which there are provided the buck-stays 6 and 7 at the 10 two sides of a door jamb 8 into which seats the door designated in its entirety by the numeral 9. These buck-stays, when used, constitute a convenient element or structure to which may be secured suitable abutments 15 for engagement by the locking devices on the door. It will be understood, however, that as far as the use of buck-stays and door jambs are concerned, the features of the present invention might be used in many 20 other associations or combinations than that illustrated in the drawings.

In the construction illustrated there are provided two of the locking devices designated by the numerals 10 and 11 respectively. 25 The use of two locking devices is generally recognized practice, and when two of these devices are used, they insure a solid and even locking of the door into position. They also serve to insure the application of a more 30 uniform lifting effort on the door, and also when used, serve to prevent the door from tilting with respect to the door machine. It will be understood, however, that in many 35 cases a single locking device may be used, and that I contemplate within the scope of my invention, the use of one or more locking devices and do not limit myself to the use of two of them except as I may do so in the claims.

40 Bearing the foregoing in mind, each locking device comprises a bracket 12 secured to the face of the door, and generally provided with two outstanding flanges 13 and 14. In some cases a single flange will be found satisfactory. Within these flanges there are provided slots 15, and extending through the flanges of each locking device is a locking pin 16 which is free to move up or down within the slots of its locking device, as will 45 be readily apparent from inspection of the several figures. Any suitable means or construction may be provided for retaining the pin in place in its locking device, as for example, a collar 17 located upon the pin at 50 a point between the flanges, and secured to the pin by a cross pin 18.

The locking pin 16 of each locking device, when in one position, is adapted to co-operate with suitable stationary abutments located, for example, on the buck-stays 6 and 7. Short sections of angle-iron 19 and 20, for example serve as convenient abutments for this purpose. These angle-irons may be held in place by bolts 21, and in order to permit the angle-irons to be exactly adjusted

and positioned, they may be provided with elongated slots 21^a for the accommodation of said bolts. These slots, when used, will serve not only to permit the abutments to be moved back and forth on the buck-stays, but 70 will also permit the abutments to be tilted, if desirable, in some cases, so that their outstanding legs will extend either in a true vertical direction, or towards or away from the face of the door itself. 75

The stationary abutments should be so positioned with respect to the locking devices that when the locking pins are in their lowered positions, their end portions will engage the abutments in a locking fashion, whereas 80 when the locking pins are raised to the extreme upper limit of permissible movement, they will clear the abutments thereby permitting the door to be removed.

In order to make sure that a firm locking 85 action will be secured, it is desirable in many cases, to so relate the slots 15 with respect to the outstanding legs of the abutments that as the locking pins are lowered, a wedging action will be secured, thus tending to force 90 the door even more securely into position within its seat. This relationship can be effected in any suitable manner, as for example by curving or slanting the slots 15, or by tilting the abutment members, or by 95 both of said expedients. In the construction illustrated the relationship may be secured in either way or both ways. For example the abutments may be tilted on the buck-stays, and the slots 15 are illustrated as being curved. It will be evident, however, as the locking pins are forced down, the door 100 will be wedged securely home.

These locking pins 16 serve as a very convenient means or element for engagement 105 by the suitable lifting elements of a door machine, and in order to show one convenient manner in which they may be thus used for lifting the door, I have illustrated a portion of the construction of a door machine 110 which I will now explain.

This door machine includes upper and lower arms 22 and 23 respectively which are pivoted to a suitable portion of the door machine at the points 24 and 25 respectively, as 115 clearly shown in Fig. 2. Means not shown in the present drawings is provided for rocking the arm 22 on its pivotal center 24 so as to raise its outer end portion 26 when the load of the door is to be taken. A link 27 is 120 provided between the arms 22 and 23 for causing them to operate in more or less unison. In the construction illustrated, the upper end of said link is pinned to the arm 22 by the pin 28. The lower end of the link 125 27 extends through the arm 23, and springs 29 and 30 are provided for engaging the upper and lower faces of said arm so that the arm is always subjected to a spring pressure, tending to cause it to travel in harmony with 130

the arm 23. Nevertheless, the two arms may be caused to move relatively with respect to each other a certain distance, but under spring pressure.

- 5 The outer or head ends 26 and 31 of the two arms 22 and 23 are bifurcated as clearly illustrated in Fig. 5 so that each of them has the jaws 32 and 33. These jaws are separated a sufficient distance to embrace the flanges 13 and 14 of the corresponding brackets 10 and 11, so that said jaws may engage both end portions of the locking pins. Each jaw is slotted as clearly shown in Figs. 2 and 4 so as to provide an upstanding finger 34 15 and an overhanging lip 35. The fingers 34 serve to securely retain the locking pins and enable the door machine to exert a sufficient pull on the door to withdraw it from the oven.

- 20 After the door has been reseated, the arms 22 and 23 are rocked so as to lower their jaws for the purpose of disengaging them from the locking pins. At the same time the overhanging lips 35 when used may be caused 25 to force the locking pins firmly downwardly with sufficient pressure to insure that the door will be wedged home in a tight manner.

When the spring device or connection 29 and 30 is used, the same will insure a proper 30 engagement of the jaws of both the upper and lower arms with the respective locking pins, the springs in such a case compensating for any slight inequalities in the spacing of the locking devices on the doors. Furthermore, 35 these spring equalizing connections when used, will insure a sufficient downward pressure on both of the locking pins to make certain a wedging action at both the upper and lower ends of the door.

- 40 It will be seen that by the use of bifurcated jaws on the lifting arms 22 and 23 in conjunction with two flanges on each door bracket there is an assurance that as the arms are raised, both ends of the locking 45 pins will be forced up, and the use of a sleeve or the like on each locking pin will insure that said locking pin will be retained in proper co-operative engagement with the door bracket.

50 I claim:

1. The combination with a coke oven door, of locking means therefor comprising a pair of brackets on the outer face of the door located at different elevations, each bracket 55 having a pair of outstanding vertical flanges, the flanges of each bracket being provided with elongated slots extending in a generally vertical direction, a locking pin extending through the slots of each bracket and having 60 its end portions adapted to engage suitable fixed stops when the door is seated, and a central sleeve on each pin between the flanges of the corresponding bracket, substantially as described.

2. The combination with a coke oven door,

of locking means therefor, comprising a bracket on the outer face of the door, a pair of vertically extending outstanding separated flanges on said bracket, there being vertically elongated slots in said flanges, a locking pin extending through said slots and having its portions projecting beyond the adjacent side portions of the door, a retaining device on the locking pin between the flanges and serving to prevent removal of the locking pin endwise through the slots, and stationary abutments having vertically extending abutment faces for engagement by the corresponding end portions of the locking pin when the locking pin is in the lower portion of the slots aforesaid, substantially as described.

3. The combination with a coke oven door, of locking means for said door, comprising a pair of vertically extending outstanding separated flanges in conjunction with the outer face of the door, there being vertically elongated slots in said flanges, a locking pin extending through said slots and having its end portions projecting beyond the sides of the door, means for retaining the locking pin in co-operative relation with the flanges aforesaid while permitting vertical movement of the pin within the slots aforesaid, and stationary stops having inwardly facing abutment faces in position for engagement by the corresponding end portions of the locking pin when said pin is in lowered position within its slots, substantially as described.

4. The combination with a coke oven door, of locking means for locking the door, comprising a transverse locking pin extending across the front face of the door and having its end portions projecting beyond the edges of the door, means for retaining said locking pin in position on the door while permitting bodily movement of the pin vertically with respect to the door, and for limiting the upward and downward movements of said pin, and suitable stationary stops having inwardly facing abutment faces for engagement by the end portions of the locking pin when said pin is in lowered position, substantially as described.

5. The combination with a coke oven door, of a locking device for said door comprising a transversely extending locking pin located adjacent to the outer face of the door and having its end portions projecting beyond the sides of the door at the points adjacent to said locking pin, means in conjunction with the door and the pin for retaining the pin in co-operative relationship with respect to the door while permitting movement of the pin bodily in a generally vertical direction with respect to the door, and for limiting the upward and downward movements of the pin, and suitable stationary stops having inwardly facing abut-

ment faces for engagement by the end portions of the locking pin when said pin is in lowered position, said abutment faces and the retaining means aforesaid being so related that when the locking pin is moved downwardly a wedging action is secured tending to force the door rearwardly, substantially as described.

6. The combination with a coke oven door, 10 of means for locking the door comprising a transversely extending locking pin vertically movable adjacent to the front face of the door bodily in a generally vertical direction, means in conjunction with the door 15 and locking pin for guiding the pin in its vertical movements, and stationary abutments having inwardly facing abutment faces for engagement by the end portions of the locking pin when the locking pin is 20 moved into locking position, said abutment faces being adjustable under the control of the operator for the purpose of insuring a wedging action as the locking pin is moved into locking position, substantially as described.

7. The combination with a coke oven door, 30 of locking and lifting means in conjunction with said door comprising a transversely extending locking pin adjacent to the front face of the door, means in conjunction with the door and said pin permitting the pin to move bodily with respect to the face of the door in a generally vertical direction and for limiting the upward and downward 35 movements of said pin, and a stationary abutment having an inwardly facing abutment face in position for engagement by the corresponding end portion of the pin when the pin is in lowered position, substantially as described.

40 8. The combination with a coke oven door,

of a transversely extending locking pin adjacent to the front face of said door, means in conjunction with the door and said pin for retaining the pin in co-operative relationship to the door while permitting bodily vertical movement of the pin, and for limiting the upward and downward movements of the pin, and suitable stationary abutments in position for engagement by the 50 end portions of the pin when the pin is in lowered position, substantially as described.

9. The combination with a coke oven door, 55 of a pair of locking pins extending across the front face of the door at different elevations, each pin being bodily movable with respect to the door in a vertical direction, means in conjunction with the door and each pin for permitting such bodily movement of the pin and for limiting the upward and 60 downward movements of the pin, and suitable wedging abutments in conjunction with the end portion of each pin, substantially as described.

10. The combination with a coke oven 65 door, of a locking and manipulating device therefor comprising a pin movable with respect to the face of the door, means in conjunction with the door and said pin for limiting the back and forth movements of the pin, and a suitable stationary abutment in conjunction with said pin for locking purposes, whereby when the lifting force is applied to said pin, the movement of the pin relatively to the door is restricted so as to insure transmission of a lifting force from the pin to the door, while permitting a sufficient movement of the pin in the other direction to at times insure a locking engagement of the pin, substantially as described.
